Appl. 22, 1831 43.

Daniel Harrington 6510X

The subscriber refers to in this Letters Patent only making part of the same containing a description in the words of the said Daniel Harrington himself of his improvement in the Fish Holder.

To all to whom these presents shall come Be it known that "Daniel Harrington of Philadelphia in the County of Philad" said State of Pennsylvania have invented a new and useful improvement in the trachea for supplying ink to the pen and that the following is a full and exact description of the construction and operation of the said machine as invented by the aforesaid before and denominated the new fish holder. The main body of this fish holder is, at the top part, three inches wide and five inches long, and at its bottom one eighth of an inch larger at its ends and sides than it is at its top. In depth it is two inches. This body of fish holder may be made of wood with a leather top or a metallic top, or the whole body may be made of wood metal or stone, as well as some other substances, as clay, plaster of Paris, &c. fine it may be made of any substance that will hold common ink of different colors. About the centre of the top of this body is sunk down within one quarter of an inch of the bottom, a round chamber for holding a supply of ink (say black ink). This chamber communicates at its side next to one end of the body with another chamber between it (the supply chamber) and the end of the body. This second chamber has a diameter, say only one and a quarter inch in diameter is sunk down to near the same depth as the larger one. Into this smaller chamber is secured from the top of the body a metallic oblong cap, say in length one and three quarters of an inch and in diameter one and a quarter inch made funnel form at the inner part of its upper end with an opening on its outer surface

of a suitable character day and quarter of an inch through which to insert a pen to receive ink. Below this opening the sides of this metallic ^{cup} are parallel and as large as the diameter of the cup will admit of and near its lowest point within is fitted a thin piece of cork with two or three holes at its sides through which the ink rises up to the lowest part of the funnel form, or hole through which the pen is inserted. This cork may be drawn upwards or pushed downwards so as to let the pen pass into the ink any given depth to suit the wishes of the writer: also the metallic cup may be descended closer into the ink or screened up at pleasure. It will be readily seen that there are two principles or ways of graduating the depth of the ink so that the pen at each dip can take but a certain quantity of ink viz. by raising or lowering the cork and by screening down or up the metallic cup. Another principle obtained in this new ink holder is that the pen can never be inserted so high up as to blacken or soil the fingers of the writer unless the cork is pushed quite too low down. Into the supply chamber in the centre of the body is screwed an oblong metallic cup and reservoir. If this supply chamber or fountain is filled, say half full ^{with} ink and the cup and reservoir is screened down as it would the ink it causes it rise in the chamber where the pen is to be inserted to any required height. Here it will be readily seen is a fourth new principle: when all the ink has become exhausted from the supply chamber or fountain, by screening up to a proper height the oblong cup (and reservoir) (and then turning a screw (upwards)) in the centre of the cup. The ink which has been previously put into the reservoir and kept in reservoir is let down through a hole in the lower end of said reservoir into the supply chamber or fountain. Here is a fifth principle and by returning said centre screw to its place the oblong

cup and reservoir may again be removed downwards at pleasure until all the ink has been forced into the other chamber of certain and used, after which, of course, a new supply must be furnished both to the supply chamber or fountain and reservoir. The part that stands in the pipe of the cup, blackened with holes in it is merely to set upon and may be retained and used or disposed with as there are holes enough in the body of the ink holder for holding certain fluid. The two smaller funnel form metallic oblong cups at the other end of the body of the ink holder for red and blue ink, are the same in all respects as the one above described except that they are less in diameter, say only three quarters of an inch in diameter. They have their appropriate chambers or fountains, in point of size but have no supply fountains. They graduate to suit the wishes of the writer by screwing up or down, also by drawing up or pushing down the ends in their lower ends. Their fountains when exhausted are supplied again with ink by pouring in at their tops. It relates to invention with reference to this new ink holder the undersigned is aware that the body of this ink holder though an oblong & square on its top is not so far different from some square forms of the old fashioned ink holder stand long in use as to be denominated a discovery or invention. The same may be said of the chambers or fountains as relates to their form & size &c. for all forms of hollow vessels from that of the body of an oyster shell to the old fashioned common ink stand have been used from time immemorial to this date. But all of the other parts of the new ink holder as above specified the undersigned merely believes to be his own inventions especially every article in motions and combinations justify him in his claim to the invention of the new ink holder. There is an addition to five new principles already above mentioned as belonging to the said ink holder

are, one more say a eighth viz: when the inholder is done
 for the day, or not wanted for a given time by screwing up-
 wards the metallic cup into which the pipe is inserted for
 the reception of ink until the ^{cone} appears naked of ink, then
 and is nearly ^{alleged} detached from the ink and the process
 of evaporation prevented, or the metallic cup may be com-
 pletely stopped by a cork or other stopper. There is likewise
 a seventh principle belonging to the new in-
 holder. If from long use dregs collects in the chambers
 or fountain by screwing out the cups the Chambers are
 readily come at by a large opening at their tops (very differ-
 ent from the old fashioned inholders) and easily washed
 out. It may be necessary to say further that the top part
 of the body of the above described inholder is leather is con-
 nected upon wood with common glue, and that the
 screws on the different cups be cut their necessary depth
 into the leather by wetting the edge of the leather on their
 first being turned into their respective places or chambers.
 The chambers of the body being made of wood should be
 filled for a short time with (hot) molten beeswax so
 that the pores of the wood may be stopped with the wax
 for the better holding of the ink after the wax has become
 hard in the pores of the wood. The out side of the body
 and part of the surface of the cups is covered with paint, say
 4, 2, or 3 coats. The inventor believes that lead or paste will
 be the metal used mostly hereafter, for both bodies and
 cups &c of the inholder as calculated to afford the in-
 holder ^{generally} at a lower price; the stone (made like the stone
 wall and burnt) may be used in part and metal in
 part. In the model accompanying this specification
 (now deposited in the patent office) the cups are also
 made of brass but one, which is made of lead. The brass
 cup and reservoir has in its top with hole in it a
 piece

6510X

piece made of tin standing on the cap, on three thin legs
as above described for to stand upon in. This piece as then
said may suspend with

Miners.
